UNITED STATES PATENT OFFICE.

CLARENCE H. FREDERICK, OF KENOSHA, WISCONSIN, ASSIGNOR TO THE SIMMONS MANUFACTURING COMPANY, OF KENOSHA, WISCONSIN, A CORPORATION OF WISCONSIN.

FABRIC-MAKING MACHINE.

1,148,766.

Specification of Letters Patent.

Patented Aug. 3, 1915.

Application filed October 23, 1913. Serial No. 796,800.

To all whom it may concern:

Be it known that I, CLARENCE H. FREDERICK, citizen of the United States, residing at Kenosha, in the county of Kenosha 5 and State of Wisconsin, have invented a certain new and useful Improvement in Fabric-Making Machines, of which the following is a full, clear, concise, and exact description, reference being had to the accompanying drawings, forming a part of this 10 specification.

My invention relates to improvements in machines for making metal fabric.

Among the salient objects of the invention are, to provide an automatic machine for building fabric from separate links; to provide in a machine for making wire link fabric composed of interengaged identical hooked links, mechanism for directly hooking 15 partially completed links into engagement with the end of a previously completed fabric length; to provide in a machine of the class described, mechanism for successively adding links to the ends of a 20 plurality of chains of which the completed fabric is composed; to provide in a machine of the class described, mechanism for directly engaging the fabric units with the fabric units of a completed fabric composed 25 of a series of longitudinal chains of interengaged fabric units; to provide a machine 30 of the general type described in which incomplete links of the fabric are first engaged with the completed links constituting 35 part of the previously formed fabric and afterward completed and thereby locked in position in the fabric; to provide a machine 40 for making an indefinite length of wire link fabric composed of a series of longitudinal chains parallel with the length 45 of the fabric and suitably held together to prevent the separation of the adjacent chains; to provide a machine of the type last described in which links are directly engaged 50 with and added to the ends of the chains of the previously formed fabric; and, in general, to provide an improved fabric-making machine of the character referred to.

My invention will be fully explained by reference to the accompanying drawings showing the preferred embodiment thereof; and in which drawings Figure 1 is a plan

view, certain parts being omitted for the sake of clearness; Fig. 2 is a view in elevation, certain parts also being omitted for the sake of clearness; Fig. 3 is a sectional view on line 3—3 of Fig. 6; Fig. 4 is a sectional view on line 4—4 of Fig. 3; Fig. 5 is a perspective view illustrating an element of construction; Fig. 6 is a sectional view on line 6—6 of Figs. 1 and 9; Fig. 7 is a sectional view on line 7—7 of Figs. 1 and 9; Fig. 8 is a sectional view on line 8—8 of Figs. 1 and 9; Fig. 9 is a sectional view 65 on line 9—9 of Fig. 1; Fig. 10 is a sectional view on line 10—10 of Fig. 1; Fig. 11 is a sectional view on line 11—11 of Fig. 2; Fig. 12 is a sectional view on line 12—12 of Fig. 11; Fig. 13 is a sectional view on 70 line 13—13 of Fig. 11; and Fig. 14 is a view illustrating one style of fabric that may be made by the machine.

Like parts are indicated by similar characters of reference throughout the different 75 figures.

Referring first to Fig. 14, there is there illustrated one form of wire link fabric that may be made by the machine, this form of fabric including a plurality of adjacent rows 80 15 (which rows in this style of fabric preferably extend crosswise of the fabric) of adjacent U-shaped units 16, the units in each row being located side by side with adjacent units of adjacent rows, adjoining portions of the base and side members of each unit being outwardly bulged at 17 while the ends of the sides of each unit opposite the base thereof are formed into eyes 18, the eyes of the side members of the units in 90 each row receiving the bulged portions of the bases of the units in the adjacent rows, and bands or links 19 preferably, though not necessarily, made of flat metal, passing about the bulged portions of the side members of adjacent units in the same row operating hingeably to connect the units joined thereby. These units may be separately made from the machine if desired, though the invention is not to be limited to such 100 separate operation, but however made, such units are received at the point indicated by the arrow 20 in Fig. 2 where they are engaged and moved by a feeding chain 21 to be assembled in accordance with my invention. 105 These units are applied separately and dis-

tinctly to the chain before the bands 19 are applied thereto, Fig. 3 showing the positions of the units upon the chain, this figure, however, showing the bands 19 as having been applied, it being unnecessary to furnish a distinct illustration showing the links as they initially appear upon the chain. The fabric units 16 are inwardly pressed down upon the belt 21 (preferably in the form of a chain), each unit being interposed between unheaded pins 22 projecting outwardly from adjacent links of the chain and between headed pins 23 carried upon the same chain links which carry the pins 22. The units 16 are thus properly alined upon the chain 21 to enable the application of the bands 19 thereto to form the units into the rows, which rows are to be formed into the fabric.

The chain 21 is intermittently moved in the direction indicated by the arrow in Fig. 2, such intermittent movement being effected by a cam 24 which operates upon a cam roller 25 mounted upon the inner end of an intermediately pivoted cam lever 26 which carries a spring pressed pawl 27 at its outer end, this pawl 27 operating to push the chain a distance, in the direction indicated by the arrow in Fig. 2, which is equal to the width of each unit where such unit is joined with its neighbors by the bands 19, such movement of the chain being positively limited by means of the stop 28 forming an extension of a die member 29 (Fig. 12), which stop 28 is forced, by means to be specified, into the path of the adjacent extension 30 of a contiguous link for this purpose and which die member 29 is moved beneath the adjacent bulges 17 for the purpose of enabling a loop 19 to be formed around them, all as will later appear. After the chain has been advanced one fabric unit space in the manner described the spring 31 places the pawl 27 into engagement with the link extension 30 of the next chain link preparatory to moving the chain the space of another fabric unit after the band 19 has been applied to previously advanced fabric units. When the chain 21 has been brought to rest after having advanced the fabric unit next to be joined in the row being formed, the adjacent bulges 17 of the newly and next precedingly advanced fabric units are positioned immediately over the die recess 32 in the die member 29 (Figs. 11, 12 and 13), after which a portion of the metal strip 33 is applied to the adjacent bulges 17 in a manner to form a hinging band 19 about the same. A portion of suitable length to form each band 19 is cut from the strip 33 by the coöperating cutting elements 34 and 35, the cutting element 34 also constituting a folding member which is accompanied by a companion folding member 36, the folding members 34 and 36 operating to depress the

ends of the portion cut from the strip 33 as indicated in dotted lines in Fig. 13, whereafter the plunger 37 operates to press the partially formed loop 19 into the die space 32 to complete the band 19 about the adjacent bulges 17. The folding members 34 and 36 are recessed as indicated at 38 properly to direct the partially formed band 19 into the die space 32, the folding members 34 and 36 reaching the upper level of the die element 29, the plunger 37 later completing its stroke. The folders 34 and 36 are depressed by means of a cam 39 keyed upon the main constantly driven shaft 40 upon which the cam 24 is also mounted, the cam 39 operating upon the cam roller 41 mounted upon an intermediately pivoted cam lever 42 having bifurcated continuations 43 resting upon the upper ends of the folders 34 and 36. After the folders 34 and 36 have been fully depressed, the springs 44 operate to elevate the same, these springs now being permitted to perform this function and in so doing to elevate the bifurcated portions 43 of the cam lever 42 preparatory to the fresh descent of the folders 34 and 36 when the succeeding band is to be applied. A plunger 37 is depressed by one end of a cam lever 37¹ whose cam roller 37² is operated upon by the cam 37³ (fixed upon the shaft 40) for this purpose. This plunger is withdrawn by means of springs 37⁴. I prefer to employ automatically operating means for feeding the strip 33, such feeding operation to be omitted when sufficient units have been formed in a given fabric row. One form of such feeding mechanism includes (Figs. 1, 2 10 and 13) a carriage 45 adapted to reciprocate upon slide guides 46 and having an outsetting shelf 47 upon which the strip 33 may rest. This carriage also pivotally supports a friction finger 48 engageable with the top of the strip 33 and pressed into such engagement by a spring 49. A cam lever 50 engages an extension 51 of the carriage 45 for moving the carriage toward the cutting element 34 the requisite distance, the cam lever 50 being operated upon for this purpose by a cam portion 52, fixed with respect to the cam element 39 through the intermediation of a cam roller 53 carried upon the cam lever 50. When the strip 33 has been sufficiently advanced the cutting elements 34 and 35 operate to cut off the length necessary to form the desired band 19. The carriage 45 is withdrawn by a spring 54, the friction finger 48 trailing over the strip 33 which is held from moving backwardly by means of a stationarily mounted finger 55 spring-pressed in a direction similar to that in which finger 48 is spring-pressed. The portion cut from the strip 33 is held in a bending anvil 56 which becomes interposed between the bending elements 34 and 36 when these bending elements

operate to depress the cut-off strip portion into the shape of a U. After the cut-off strip portion has been formed into a U and this U-shaped portion has been properly received 5 between the bending elements 34 and 36 the bending anvil is withdrawn.

The mechanism for effecting the withdrawal of the bending anvil 56 desirably includes the plunger 37 which is chamfered at 10 58 to engage a chamfered portion 59 of the bending anvil 56 when the plunger 37 descends thereby to thrust the bending anvil clear of the path of the plunger 37. The mechanism for restoring the bending anvil 15 56 to that position in which the folders 34 and 36 may operate upon the strip portion held by the bending anvil includes a centrally pivoted lever 60 having an inclined portion 61 engaged by an inclined portion 20 62 upon the plunger 37 when this plunger is withdrawn by the springs 37⁴. After the plunger 37 has been withdrawn the die 29 is moved backwardly by the compression spring 63, the cam 64 which previously operated upon the cam roller 65 carried by the cam lever 66 for moving the die 29 forwardly into position now being so placed to permit the spring 63 to effect such withdrawal of the die 29. When the die 29 is 25 thus positioned the chain stop 28 carried thereby is withdrawn from the path of the link projection 30 previously engaged thereby after which the chain 21 may be advanced the space of another fabric unit 16 30 whereupon the die 29 is again advanced and another band 19 is again formed in the manner previously described, assuming that the full quota of fabric units has not, as yet, been assembled in a unit row.

35 A predetermined number of fabric units having been assembled into a fabric row, the next band forming operation is omitted and the formed fabric row is dislodged from the chain 21 preferably during the 40 process of being united with another similarly formed fabric row. I preferably employ the same control mechanism for omitting the band forming function when the desired number of fabric units have been 45 assembled in one row and for also dislodging a formed row from the carrier chain 21, though the latter function is preferably performed at a later period and after a number of units in a new fabric unit row has been 50 united. The omission of the band-forming function is preferably accomplished by retaining the carriage 45 in its advanced position toward the cutter 34, 35 a sufficient 55 length of time for this purpose. That is 60 the return of the carriage 45 away from the cutter 34, 35 is delayed a length of time necessary to omit the formation of one band. To this end the cam lever 50 carries a pin 65 67 (Figs. 1 and 10) which is adapted to be engaged by a holding dog 68 to hold the

front end of the cam lever 50 in its forward position so that the spring 54 cannot return the carriage 45. Normally the holding dog 68 is withdrawn from the range of the pin 67, this dog being presented within range 70 of this pin, for the purpose of holding the carriage 45 in its forward position, by means of a lug 69 mounted upon the ratchet wheel 70 (Fig. 7), the ratchet wheel 70 having as many teeth as there are links in a row, 75 this ratchet wheel being turned one tooth upon each union of adjacent units. The ratchet wheel is turned by means of a pin 71 upon the cam 24, this pin engaging the downwardly projecting arm 72 of the bell 80 crank lever 73 which carries upon its other arm an actuating pawl 74 which is caused to move one step each time the pin 71 strikes the bell crank at 72. The lug 69 is thus moved step by step toward an arm 75 fixed 85 with respect to the arm 68. When the element 69 strikes the element 75 it moves the arm 68 into the path of the pin thereby to hold the carriage 45 in its forward position. When the lug 69 passes the arm 75 the 90 spring 76 restores the arm 68 whereupon the carriage 45 may be restored by the spring 54 preparatory to a renewal of the arrested feeding of the stock 33. The formation of the bands 19 is now resumed, a number of 95 units of a new row being first assembled by the formation of these bands 19 while the previously completed row is still being carried by the chain 21. When the row last finished has reached the place of its delivery from the chain as shown in Fig. 3 it is joined with the row next previously formed by having the bulged portions 17 of the units composing the same caught in the open eyes 18 of the previously formed row, 100 these open eyes being closed (to make the joining of the rows permanent) at a later stage in the operation of the machine by a compressor for bending portions of fabric units into permanent engagement with portions of other fabric units, this compressor 105 preferably comprising a hammer 77 which presses the eyes closed upon an anvil 78. The hammer 77 is vertically reciprocable, 110 being positively driven in both directions by rollers 79 between which a driven eccentric 80 is interposed, this eccentric being keyed upon shaft 81 to impart motion to another eccentric similarly keyed upon shaft 81 at the other side of the hammer 77 in 115 Fig. 9 there to operate upon rollers similar to rollers 79 similarly related to the hammer 77.

A complete row of links is removed from the chain 21 by the reel 82 which receives 120 the same, this reel 82 being operated by the cam 83 working upon a cam roller 84 upon one end of a cam lever 85 whose other end engages the top end of a rack 86 in mesh with a pinion 87 co-axial with the reel 82. 125

The pinion 87 is thus rotated in a counter-clockwise direction when the rack 86 descends and in a clockwise direction when the rack is elevated, the elevation of the rack being accomplished by a spring 88 engaging an extension of the pinion 87 which is thus constituted an oscillating pinion whose teeth are discontinued where the extension that engages the spring 88 is provided. The reel 82 is fixed on the shaft 89, in which shaft 10 ratchet teeth are cut which are adapted to be engaged by a spring pressed pawl 90 carried by the pinion 87. The pawl 90 operates to turn the reel when the rack 86 is moved downwardly, this pawl escaping the teeth when the rack is moved upwardly whereby the reel is given an intermittent counter-clockwise rotation. To maintain the reel in each position to which it is relatively stepped the shaft 89 turns in a friction clamp 89¹. Each time the reel turns it presents the unit enlargements 17 of a previously formed row to the eyes 18 of the last formed row, these eyes being hooked into said enlargements as the reel turns and as the eyes are being hooked into the enlargements 17 the last formed row is in process of removal from the chain 21. The last formed row of units is stripped from the chain by means of a U-shaped stripper 91 which straddles the upper stretch of the chain 21 from beneath, one side of this stripper carrying a guide 92 which is provided for co-operation with the chain to direct the travel of the row of units. The U-shaped stripper 91 is operated by a pair of levers 93 fixed with respect to a common lever 94, these levers being pivotally mounted upon a shaft 95. The lever 94 carries a roller 96 working upon a cam 97 to elevate the levers 93 to operate the stripper 91, the levers 93 being sufficiently weighted to enable the stripper 91 to descend when permitted so to do by the cam 97. A spring 45 pressed depressor 98 operates to maintain the row of units newly acquired by the reel 82 in engagement with such reel 82, such reel being provided with lugs 99 for positioning the links thereupon. A stop 100 engages the headed pins 22 so that the stripper 91 may dislodge the fabric units from engagement with said pins, this stop 100 at the same time serving to prevent the chain and the row of units carried thereby from materially departing from the plane they previously occupied so that the row of units which is about to be applied to the reel 82 is maintained in position so to be applied.

The cams 83 and 97 are in fixed relation, 60 these cams being governed by the mechanism which will now be described particularly in connection with Figs. 1, 6, 7 and 9. A quill shaft 101 is enlarged at its left-hand end there to support a pin 102 and a spring 65 103 for engaging a lug 104 carried upon pin

102 to press this pin to the left when permitted so to do by the cam lever 105. This cam lever is provided with an inclined portion 106 (Figs. 7 and 9). The pin 102 has a slot cut across the same near its right hand end to receive the lever 105 whereby this lever is able to hold the pin against the force of the spring 104. This engagement of the lever 105 and pin 102 is normal, being maintained by the normal engagement of 75 the nose 107 upon the lever 105 with the periphery of the disk 108 which is fixed with respect to the ratchet wheel 70. When the cams 83 and 97 are to operate, the lever 105 is lifted by the spring 109, the nose 107 then being in register with the notch 110 in the periphery of the disk 108, a result which occurs after a number of units in a new row have been united, the completely formed row being advanced several unit spaces before it is assembled with or joined to a pre- 80 cedingly formed row and stripped from the chain 21. When the lever 105 is thus lifted it is withdrawn from engagement with the pin 102 so that this pin is pressed to the left 90 by the spring 103 and is brought into engagement with the cam 24 fixed upon the shaft 40. The shaft 40 now communicates rotary motion to the quill shaft 101 upon which the cams 83 and 97 are fixed whereby 95 the cams 83 and 97 are operated. The extreme lower point of the inclined portion 106 is always in line with the slot or notch in the right hand end of the pin 102 irrespective of the position of this pin so that 100 the inclined portion 106 is operative to retract the pin 102 against the force of the spring 104 after the nose 107 has ridden out of the notch 110, the cams 83 and 97 then being uncoupled and remaining uncoupled until a newly formed row of fabric units is to be discharged from the chain 21. When a completed row of fabric units is being discharged from the chain 21 a previously 110 formed row of units is elsewhere, in the normal operation of the machine, being permanently joined to another row of units, as indicated in Fig. 6, to which end the cams 80 are operated simultaneously with the 115 cams or eccentrics 83 and 97.

Both of the cams 80 are keyed upon the shaft 81, which has no connection with the shaft 40, but is driven by a shift-pin 111 slidably mounted in the body of the cams 83 and 97, said pin 111 engaging an aperture in the side of the left-hand cam 80. When a predetermined number of rows of fabric units have been assembled to form a fabric of predetermined length the pin 111 is withdrawn from the left hand cam 80 so that the cams 83 and 97 will, at one interval of their operation, perform their functions unaccompanied by movement of the cams 80 whereby a formed row of units may be withdrawn from the chain 21 while a permanent row 125 130

joining operation is omitted due to the temporary quiescence of the hammer 77, the temporarily hooked units of adjacent rows of different fabrics being easily separated. The 5 mechanism for withdrawing the pin 111 for the purpose of omitting permanent row joining operations will be described particularly in connection with Figs. 6, 8 and 9. The teeth of the ratchet wheel 112 equal the 10 number of rows of fabric units that are to be included in the completed fabric. This ratchet wheel is fixed upon a shaft 113 upon which a bell-crank 114 is also fixed, this bell-crank carrying a ratchet pawl 115 for 15 turning the ratchet wheel 112 one tooth for each row, this movement of the ratchet wheel 112 happening to occur as each fabric row is stripped from the chain 21 and being effected by means of the engagement of the 20 pin 116, moving with the cams 83, 97, with the lower rack of the bell-crank 114, to move the bell-crank 114 in a clockwise direction (Figs. 8 and 9) to move the ratchet wheel 112 one step. When the ratchet wheel 112 25 is being moved during the last step of its cycle, the lug 117 carried by the ratchet wheel strikes the nose 118 projecting upwardly from a cam lever 119 to depress this cam lever (which is normally elevated by a 30 spring 120) whereby the cam end 121 of the lever 119 is brought into the path of slot 122 in the pin 111 so that the pin and cam lever are engaged by the moving cams 83 and 97, the cam lever thereby effecting the withdrawal of the pin 111 against the force of 35 the spring 123 that is normally effective in maintaining the cams 83 and 97 in fixed relation with the left hand cam 80. After the 40 cams 80 have been uncoupled from the cams 83 and 97 a sufficient length of time to effect an omission of one operation of the hammer 77, the lug 117 is brought by the next step of the wheel 112 out of engagement with the pin 116 whereupon the spring 120 will withdraw the lever 119 to permit the spring 123 to restore the pin 111 to its normal position 45 in which this pin couples the cams 83 and 97 with the left hand cam 80. A tension spring 124 pulls inwardly upon the shafts 125 and 50 126 which carry the ratchet wheels 70 and 112 and the bell-crank levers 73 and 114, these shafts having shoulders 127 which are pressed inwardly by the spring 124 whereby the elements 70 and 108 are pressed against 55 the leather washer 128 and the element 112 is pressed against the leather washer 129, all of the elements supported upon the shafts 125 and 126 being movable with respect thereto, the leather washers 128 and 129 serving, by friction, to hold the elements 70, 60 108 and 112 in the position to which they are actuated. I do not limit myself to means for permanently joining adjacent rows of fabric units nor to means for permanently joining units in rows. 65

While the mechanism shown particularly well in Fig. 6 is primarily designed to assemble rows of units, it is obvious that inasmuch as it joins adjacent units of adjacent rows to form a fabric it may also be employed to join adjacent units to form a single row of fabric units and the invention is not therefore to be limited to the formation of a complete fabric. 70

While I have herein shown and particularly described the preferred embodiment of my invention I do not wish to be limited to the precise details of construction shown as changes may readily be made without departing from the spirit of the invention. 75

Having thus described my invention I claim as new and desire to secure by Letters Patent the following:—

1. A fabric-making machine, comprising in combination, means for positioning a succession of separate fabric units in disconnected rows of units, mechanism for joining together rows of fabric units, and mechanism for conveying a disconnected row of positioned fabric units to the mechanism for joining the rows of fabric units. 85

2. A fabric-making machine, comprising in combination, mechanism for progressively positioning separate fabric units in successive independent, transverse rows of 95 fabric units, mechanism for successively joining said rows of positioned fabric units, one row at a time, to the end of a finished fabric, and mechanism for successively bringing said rows of positioned fabric 100 units within working range of the row-joining mechanism.

3. A fabric making machine including mechanism for assembling fabric units into rows of fabric units; mechanism for joining rows of assembled fabric units; reel mechanism for transferring rows of assembled fabric units to the row-joining mechanism; and a conveyer belt for conveying the rows of assembled fabric units to 105 the reel mechanism. 110

4. A fabric making machine including mechanism for assembling fabric units into rows of fabric units; mechanism for joining rows of assembled fabric units; reel mechanism for transferring rows of assembled fabric units to the row-joining mechanism; and a conveyer belt for conveying the rows of assembled fabric units to the reel mechanism, said belt being so positioned with respect to the reel mechanism that the reel mechanism is adapted to present rows of fabric units previously applied thereto in such position to rows of fabric units conveyed thereto by the belt as to enable the 115 reel mechanism to effect interengagement between the fabric units applied thereto and the fabric units presented to these fabric units by the belt. 120

5. A fabric making machine including 125

mechanism for assembling fabric units into rows of fabric units; mechanism for joining rows of assembled fabric units; reel mechanism for transferring rows of assembled fabric units to the row-joining mechanism; a conveyer belt for conveying the rows of assembled fabric units to the reel mechanism; and stripping mechanism for stripping the rows of fabric units from the belt preparatory to their withdrawal by the reel mechanism.

6. A fabric making machine including mechanism for assembling fabric units into rows of fabric units; mechanism for joining rows of assembled fabric units; reel mechanism for transferring rows of assembled fabric units to the row-joining mechanism; a conveyer belt for conveying the rows of assembled fabric units to the reel mechanism, said belt being so positioned with respect to the reel mechanism that the reel mechanism is adapted to present rows of fabric units previously applied thereto in such position to rows of fabric units conveyed thereto by the belt as to enable the reel mechanism to effect interengagement between the fabric units applied thereto and the fabric units presented to these fabric units by the belt; and stripping mechanism for stripping the rows of fabric units from the belt preparatory to their withdrawal by the reel mechanism.

7. A fabric making machine including mechanism for assembling fabric units into rows of fabric units; mechanism for joining rows of assembled fabric units; mechanism for conveying the rows of assembled fabric units to the mechanism for joining the rows of fabric units; means for conveying the single fabric units to the mechanism for joining the same in rows; and means for causing the unit-joining function to be omitted when predetermined numbers of units have been assembled in the fabric rows.

45 8. A fabric making machine including mechanism for positioning fabric units into independent rows of fabric units; mechanism for joining rows of positioned fabric units one row at a time; mechanism for bringing rows of positioned fabric units within working range of the row-joining mechanism one row at a time; means for conveying the single fabric units to the mechanism for positioning the same in rows; and means for causing the unit-positioning function for each row to be discontinued when predetermined numbers of units have been positioned in the fabric rows.

60 9. A fabric making machine including mechanism for assembling fabric units into rows of fabric units; mechanism for joining rows of assembled fabric units; reel mechanism for transferring rows of assembled fabric units to the row-joining mechanism; a conveyer belt for conveying the rows of as-

sembled fabric units to the reel mechanism; means for conveying the single fabric units to the mechanism for joining the same in rows; and means for causing the unit-joining function to be omitted when predetermined numbers of units have been assembled in the fabric rows. 70

10. A fabric making machine including mechanism for assembling fabric units into rows of fabric units; mechanism for joining rows of assembled fabric units; reel mechanism for transferring rows of assembled fabric units to the row-joining mechanism; a conveyer belt for conveying the rows of assembled fabric units to the reel mechanism, said belt being so positioned with respect to the reel mechanism that the reel mechanism is adapted to present rows of fabric units previously applied thereto in such position to rows of fabric units conveyed thereto by the belt as to enable the reel mechanism to effect interengagement between the fabric units applied thereto and the fabric units presented to these fabric units by the belt; means for conveying the single fabric units to the mechanism for joining the same in rows; and means for causing the unit-joining function to be omitted when predetermined numbers of units have been assembled in the fabric rows. 85 90

11. A fabric making machine including mechanism for assembling fabric units into rows of fabric units; mechanism for joining rows of assembled fabric units; reel mechanism for transferring rows of assembled fabric units to the row-joining mechanism; a conveyer belt for conveying the rows of assembled fabric units to the reel mechanism; stripping mechanism for stripping the rows of fabric units from the belt preparatory to their withdrawal by the reel mechanism; means for conveying the single fabric units to the mechanism for joining the same in rows; and means for causing the unit-joining function to be omitted when predetermined numbers of units have been assembled in the fabric rows. 100 105

12. A fabric making machine including mechanism for assembling fabric units into rows of fabric units; mechanism for joining rows of assembled fabric units; reel mechanism for transferring rows of assembled fabric units to the row-joining mechanism; a conveyer belt for conveying the rows of assembled fabric units to the reel mechanism, said belt being so positioned with respect to the reel mechanism that the reel mechanism is adapted to present rows of fabric units previously applied thereto in such position to rows of fabric units conveyed thereto by the belt as to enable the reel mechanism to effect interengagement between the fabric units applied thereto and the fabric units presented to these fabric units by the belt; stripping 115 120 125 130

- mechanism for stripping the rows of fabric units from the belt preparatory to their withdrawal by the reel mechanism; means for conveying the single fabric units to the mechanism for joining the same in rows; and means for causing the unit-joining function to be omitted when predetermined numbers of units have been assembled in the fabric rows.
- 10 13. A fabric making machine including mechanism for assembling fabric units into rows of fabric units; mechanism for joining rows of assembled fabric units; mechanism for conveying the rows of assembled fabric units to the mechanism for joining the rows of fabric units; and means for causing the row-joining function to be omitted when it has joined predetermined numbers of fabric unit rows into fabrics.
- 15 14. A fabric making machine including mechanism for positioning fabric units in independent rows of fabric units; mechanism for joining rows of positioned fabric units one row at a time; mechanism for bringing rows of positioned fabric units within working range of the row-joining mechanism one at a time; and means for causing the row-joining function to be omitted when it has joined predetermined numbers of fabric unit rows into fabrics.
- 20 15. A fabric making machine including mechanism for assembling fabric units into rows of fabric units; mechanism for joining rows of assembled fabric units; reel mechanism for transferring rows of assembled fabric units to the row-joining mechanism; a conveyer belt for conveying the rows of assembled fabric units to the reel mechanism; and means for causing the row-joining function to be omitted when it has joined predetermined numbers of fabric-unit rows into fabrics.
- 25 35 16. A fabric making machine including mechanism for assembling fabric units into rows of fabric units; mechanism for permanently joining rows of assembled fabric units; reel mechanism for transferring rows of assembled fabric units to the row-joining mechanism; a conveyer belt for conveying the rows of assembled fabric units to the reel mechanism; and means for causing the row-joining function to be omitted when it has joined predetermined numbers of fabric-unit rows into fabrics.
- 30 40 45 50 55 60 65 17. A fabric making machine including mechanism for assembling fabric units into rows of fabric units; mechanism for permanently joining rows of assembled fabric units; reel mechanism for transferring rows of assembled fabric units to the row-joining mechanism; a conveyer belt for conveying the rows of assembled fabric units to the reel mechanism, said belt being so positioned with respect to the reel mechanism that the reel mechanism is adapted to present rows of fabric units previously applied thereto in such position to rows of fabric units conveyed thereto by the belt as to enable the reel mechanism to effect interengagement between the fabric units applied thereto and the fabric units presented to these fabric units by the belt; and means for causing the row-joining function to be omitted when it has joined predetermined numbers of fabric-unit rows into fabrics.
18. A fabric making machine including mechanism for assembling fabric units into rows of fabric units; mechanism for permanently joining rows of assembled fabric units; reel mechanism for transferring rows of assembled fabric units to the row-joining mechanism; a conveyer belt for conveying the rows of assembled fabric units to the reel mechanism, said belt being so positioned with respect to the reel mechanism that the reel mechanism is adapted to present rows of fabric units previously applied thereto in such position to rows of fabric units conveyed thereto by the belt as to enable the reel mechanism to effect interengagement between the fabric units applied thereto and the fabric units presented to these fabric units by the belt; stripping mechanism for stripping the rows of fabric units from the belt preparatory to their withdrawal by the reel mechanism; and means for causing the row-joining function to be omitted when it has joined predetermined numbers of fabric-unit rows into fabrics.
19. A fabric making machine including mechanism for assembling fabric units into rows of fabric units; mechanism for joining rows of assembled fabric units; mechanism for conveying the rows of assembled fabric units to the mechanism for joining the rows of fabric units; means for conveying the single fabric units to the mechanism for joining the same in rows; means for causing the unit-joining function to be omitted when predetermined numbers of units have been assembled in the fabric rows; and means for causing the row-joining function to be omitted when it has joined predetermined numbers of fabric-unit rows into fabrics.
20. A fabric making machine including mechanism for positioning fabric units into independent disconnected rows of fabric units; mechanism for joining rows of positioned fabric units; mechanism for bringing rows of positioned fabric units within working range of the row-joining mechanism one row at a time; means for conveying the single fabric units to the mechanism for joining the same in rows; means for causing the unit-joining function to be omitted when predetermined numbers of units have been assembled in the fabric rows; and means for causing the row-joining function to be omitted when it has joined predetermined numbers of fabric-unit rows into fabrics.

units have been positioned in the fabric rows; and means for causing the row-joining function to be omitted when it has joined predetermined numbers of fabric-unit rows into fabrics.

- 5 21. A fabric making machine including mechanism for assembling fabric units into rows of fabric units; mechanism for joining rows of assembled fabric units; reel mechanism for transferring rows of assembled fabric units to the row-joining mechanism; a conveyer belt for conveying the rows of assembled fabric units to the reel mechanism; means for conveying the single fabric units to the mechanism for joining the same in rows; means for causing the unit-joining function to be omitted when predetermined numbers of units have been assembled in the fabric rows; and means for causing the row-joining function to be omitted when it has joined predetermined numbers of fabric-unit rows into fabrics.
- 10 22. A fabric making machine including mechanism for assembling fabric units into rows of fabric units; mechanism for permanently joining rows of assembled fabric units; reel mechanism for transferring rows of assembled fabric units to the row-joining mechanism; a conveyer belt for conveying the rows of assembled fabric units to the reel mechanism, said belt being so positioned with respect to the reel mechanism that the reel mechanism is adapted to present rows of fabric units previously applied thereto in such position to rows of fabric units conveyed thereto by the belt as to enable the reel mechanism to effect interengagement between the fabric units applied thereto and the fabric units presented to these fabric units by the belt; means for conveying the single fabric units to the mechanism for joining the same in rows; means for causing the unit-joining function to be omitted when predetermined numbers of units have been assembled in the fabric rows; and means for causing the row-joining function to be omitted when it has joined predetermined numbers of fabric-unit rows into fabrics.
- 15 23. A fabric making machine including mechanism for assembling fabric units into rows of fabric units; mechanism for joining rows of assembled fabric units; reel mechanism for transferring rows of assembled fabric units to the row-joining mechanism; a conveyer belt for conveying the rows of assembled fabric units to the reel mechanism; stripping mechanism for stripping the rows of fabric units from the belt preparatory to their withdrawal by the reel mechanism; means for conveying the single fabric units to the mechanism for joining the same in rows; means for causing the unit-joining function to be omitted when predetermined numbers of units have been assembled in the fabric rows; and means for causing the row-joining function to be omitted when it has joined predetermined numbers of fabric-unit rows into fabrics.
- 20 24. A fabric making machine including mechanism for assembling fabric units into rows of fabric units; mechanism for permanently joining rows of assembled fabric units; reel mechanism for transferring rows of assembled fabric units to the row-joining mechanism; a conveyer belt for conveying the rows of assembled fabric units to the reel mechanism, said belt being so positioned with respect to the reel mechanism that the reel mechanism is adapted to present rows of fabric units previously applied thereto in such position to rows of fabric units conveyed thereto by the belt as to enable the reel mechanism to effect interengagement between the fabric units applied thereto and the fabric units presented to these fabric units by the belt; stripping mechanism for stripping the rows of fabric units from the belt preparatory to their withdrawal by the reel mechanism; means for conveying the single fabric units to the mechanism for joining the same in rows; means for causing the unit-joining function to be omitted when predetermined numbers of units have been assembled in the fabric rows; and means for causing the row-joining function to be omitted when it has joined predetermined numbers of fabric-unit rows into fabrics.
- 25 25. In a fabric-assembling mechanism, a work-holding mechanism, a fabric-support, means for positioning a series of fabric units upon said work-holding mechanism, and means for effecting relative movement of the row of units so positioned on the work-holding mechanism and the fabric-support whereby the several units of said row are directly engaged with and added to the previously formed fabric.
- 30 26. In a fabric-assembling mechanism, a work-holding mechanism, a fabric-holding mechanism, means for successively uniting and positioning a series of connected units upon said work-holding mechanism, and means for effecting relative movement of the row of units so united and positioned on the work-holding mechanism and the fabric whereby the several units of said row are simultaneously directly engaged with and united to the previously formed fabric.
- 35 27. A fabric making machine including mechanism for joining rows of fabric units; mechanism for conveying rows of fabric units to said row-joining mechanism; reel mechanism for transferring rows of fabric units to the row-joining mechanism; and a conveyer belt for conveying the rows of fabric units to the reel mechanism.
- 40 28. A fabric making machine including mechanism for joining rows of fabric units; mechanism for conveying rows of fabric units to the reel mechanism.

causing the row-joining function to be omitted when it has joined predetermined numbers of fabric-unit rows into fabrics.

45 24. A fabric making machine including mechanism for assembling fabric units into rows of fabric units; mechanism for permanently joining rows of assembled fabric units; reel mechanism for transferring rows of assembled fabric units to the row-joining mechanism; a conveyer belt for conveying the rows of assembled fabric units to the reel mechanism, said belt being so positioned with respect to the reel mechanism that the reel mechanism is adapted to present rows of fabric units previously applied thereto in such position to rows of fabric units conveyed thereto by the belt as to enable the reel mechanism to effect interengagement between the fabric units applied thereto and the fabric units presented to these fabric units by the belt; stripping mechanism for stripping the rows of fabric units from the belt preparatory to their withdrawal by the reel mechanism; means for conveying the single fabric units to the mechanism for joining the same in rows; means for causing the unit-joining function to be omitted when predetermined numbers of units have been assembled in the fabric rows; and means for causing the row-joining function to be omitted when it has joined predetermined numbers of fabric-unit rows into fabrics.

50 25. In a fabric-assembling mechanism, a work-holding mechanism, a fabric-support, means for positioning a series of fabric units upon said work-holding mechanism, and means for effecting relative movement of the row of units so positioned on the work-holding mechanism and the fabric-support whereby the several units of said row are directly engaged with and added to the previously formed fabric.

55 26. In a fabric-assembling mechanism, a work-holding mechanism, a fabric-holding mechanism, means for successively uniting and positioning a series of connected units upon said work-holding mechanism, and means for effecting relative movement of the row of units so united and positioned on the work-holding mechanism and the fabric whereby the several units of said row are simultaneously directly engaged with and united to the previously formed fabric.

60 27. A fabric making machine including mechanism for joining rows of fabric units; mechanism for conveying rows of fabric units to said row-joining mechanism; reel mechanism for transferring rows of fabric units to the row-joining mechanism; and a conveyer belt for conveying the rows of fabric units to the reel mechanism.

65 28. A fabric making machine including mechanism for joining rows of fabric units; mechanism for conveying rows of fabric units to the reel mechanism.

- units to said row-joining mechanism; reel mechanism for transferring rows of fabric units to the row-joining mechanism; and a conveyer belt for conveying the rows of fabric units to the reel mechanism, said belt being so positioned with respect to the reel mechanism that the reel mechanism is adapted to present rows of fabric units previously applied thereto in such position to rows of fabric units conveyed thereto by the belt as to enable the reel mechanism to effect interengagement between the fabric units applied thereto and the fabric units presented to these fabric units by the belt.
29. A fabric making machine including mechanism for joining rows of fabric units; mechanism for conveying rows of fabric units to said row-joining mechanism; reel mechanism for transferring rows of fabric units to the row-joining mechanism; a conveyer belt for conveying the rows of fabric units to the reel mechanism; and stripping mechanism for stripping the rows of fabric units from the belt preparatory to their withdrawal by the reel mechanism.
30. A fabric making machine including mechanism for joining rows of fabric units; mechanism for conveying rows of fabric units to said row-joining mechanism; reel mechanism for transferring rows of fabric units to the row-joining mechanism; a conveyer belt for conveying the rows of fabric units to the reel mechanism, said belt being so positioned with respect to the reel mechanism that the reel mechanism is adapted to present rows of fabric units previously applied thereto in such position to rows of fabric units conveyed thereto by the belt as to enable the reel mechanism to effect interengagement between the fabric units applied thereto and the fabric units presented to these fabric units by the belt; and means for causing the row-joining function to be omitted when it has joined predetermined numbers of fabric-unit rows into fabrics.
31. A fabric making machine including mechanism for joining rows of fabric units; mechanism for conveying rows of fabric units to said row-joining mechanism; and means for causing the row-joining function to be omitted when it has joined predetermined numbers of fabric-unit rows into fabrics.
32. In a machine for making fabric composed of a series of rows of laterally interengaged fabric units, the combination of mechanism for interengaging rows of fabric units, one row at a time, mechanism for bringing fabric unit rows, one row at a time, within working range of the row-joining mechanism, and means for temporarily suspending the operation of the row-joining mechanism after a predetermined number of rows of fabric units have been laterally interengaged.
33. A fabric making machine including mechanism for joining rows of fabric units; mechanism for conveying rows of fabric units to said row-joining mechanism; reel mechanism for transferring rows of fabric units to the row-joining mechanism; a conveyer belt for conveying the rows of fabric units to the reel mechanism; and means for causing the row-joining function to be omitted when it has joined predetermined numbers of fabric-unit rows into fabrics.
34. A fabric making machine including mechanism for permanently joining rows of fabric units; mechanism for conveying rows of fabric units to said row-joining mechanism; reel mechanism for transferring rows of fabric units to the row-joining mechanism; a conveyer belt for conveying the rows of fabric units to the reel mechanism, said belt being so positioned with respect to the reel mechanism that the reel mechanism is adapted to present rows of fabric units previously applied thereto in such position to rows of fabric units conveyed thereto by the belt as to enable the reel mechanism to effect interengagement between the fabric units applied thereto and the fabric units presented to these fabric units by the belt; and means for causing the row-joining function to be omitted when it has joined predetermined numbers of fabric-unit rows into fabrics.
35. A fabric making machine including mechanism for joining rows of fabric units; mechanism for conveying rows of fabric units to said row-joining mechanism; reel mechanism for transferring rows of fabric units to the row-joining mechanism; a conveyer belt for conveying the rows of fabric units to the reel mechanism; stripping mechanism for stripping the rows of fabric units from the belt preparatory to their withdrawal by the reel mechanism; and means for causing the row-joining function to be omitted when it has joined predetermined numbers of fabric-unit rows into fabrics.
36. A fabric making machine including mechanism for permanently joining rows of fabric units; mechanism for conveying rows of fabric units to said row-joining mechanism; reel mechanism for transferring rows of fabric units to the row-joining mechanism; a conveyer belt for conveying the rows of fabric units to the reel mechanism, said belt being so positioned with respect to the reel mechanism that the reel mechanism is adapted to present rows of fabric units previously applied thereto in such position to rows of fabric units conveyed thereto by the belt as to enable the reel mechanism to effect interengagement between the fabric units applied thereto and the fabric units

presented to these fabric units by the belt; stripping mechanism for stripping the rows of fabric units from the belt preparatory to their withdrawal by the reel mechanism; and means for causing the row-joining function to be omitted when it has joined predetermined numbers of fabric-unit rows into fabrics.

37. A machine for assembling fabric units into rows including fabric unit joining mechanism; means for feeding units that are to be joined to said unit-joining mechanism; and means for causing the unit-joining function to be omitted when predetermined numbers of units have been assembled in the fabric rows.

38. A machine for assembling fabric units into rows including mechanism for applying fabric unit joining elements to adjacent fabric units; means for feeding units and unit-joining elements to said unit-joining mechanism; and means for causing the unit-joining function to be omitted when predetermined numbers of units have been assembled in the fabric rows.

39. A machine for assembling fabric units including a compressor for bending portions of fabric units into permanent engagement with portions of other fabric units; mechanism for directing a series of interconnected fabric units to the compressor; and means for arresting the portions of adjacent fabric units that are to be permanently engaged in position to be operated upon by said compressor.

40. A machine for assembling fabric units including a compressor for bending portions of fabric units into permanent engagement with portions of other fabric units; a reel for directing a series of interconnected fabric units to the compressor; and means for arresting the portions of adjacent fabric units that are to be permanently engaged in position to be operated upon by said compressor.

45. A machine for joining fabric units including a reel; and means for conveying fabric units thereto in position to enable them to have engagement with fabric units previously applied to the reel.

42. A machine for joining fabric units including a reel; and a conveyer belt operating to convey fabric units to said reel in position to enable the conveyed fabric units to engage fabric units previously applied to the reel.

43. A machine for joining fabric units including a reel; a conveyer belt operating to convey fabric units to said reel in position to enable the conveyed fabric units to engage fabric units previously applied to the reel; and means for arresting the belt while the fabric units are presented thereby to fabric units upon the reel.

65 44. A machine for joining fabric units

including a reel; a conveyer belt operating to convey fabric units to said reel in position to enable the conveyed fabric units to engage fabric units previously applied to the reel; and stripping mechanism for stripping the fabric units from the belt.

45. A machine for joining fabric units including a reel; a conveyer belt operating to convey fabric units to said reel in position to enable the conveyed fabric units to engage fabric units previously applied to the reel; means for arresting the belt while the fabric units are presented thereby to fabric units upon the reel; and stripping mechanism for stripping the fabric units from the belt.

46. The combination of a support for a length of fabric composed of a succession of transverse rows of fabric units, said units each having a hook at one side of the row and an eye at the other side, and row-joining mechanism for connecting the rows of units, one row at a time, to the last connected row of the fabric by engaging the eyes on one side of one row with the hooks on the adjacent side of the other row.

47. The combination of a support for carrying a length of fabric, composed of a succession of transverse rows of interconnected fabric units, means for disposing a succession of fabric units in a transverse row parallel to the transverse rows of the fabrics on said support, means for effecting relative movement of said row and the fabric on said support to bring the units of a disconnected row of fabric units into direct registration and engagement with the units of the row previously connected to the fabric, and means for finally locking said rows together.

48. The combination of a support for carrying a length of wire fabric, composed of a succession of connected rows of fabric units, each of said units having a mating hook part at one side of the row and a mating eye part at the other side of the row, and means for interengaging the mating parts of the units of the preceding rows of fabric with the companion mating parts of the units of a succeeding row.

49. The combination of a support for carrying a length of wire fabric, composed of a succession of connected rows of fabric units, each of said units being identical and having a hook part at one side of the row and a mating eye part at the other side of the row, means for directly interengaging the interfitting parts of the units of a preceding row of the fabric and a succeeding row, and means for effecting relative movement of the fabric as a whole with reference to said engaging means.

50. The combination of a movable support for carrying a length of wire fabric, composed of a succession of rows of fabric

units, each of said units having a hook on one side of the row and a bight on the other side of the row, means for positioning units, one at a time, to form a succeeding row of 5 units in the fabric, means for directly interengaging the hooks and bights of the adjacent units in the adjacent preceding row of units in the completed fabric and the succeeding row of units about to become part 10 of said fabric, and means for effecting successively relative movements of the fabric on said support and said interengaging mechanism.

51. In a machine for making wire fabric, 15 composed of a succession of rows of fabric units, each of said units having a hook part at one side of the row and a mating eye part at the other side of the row, the male parts of one row being interengaged with the adjacent female parts of the adjacent row, a support for the completed fabric, step-by-step mechanism for effecting relative unit-space movements of said support with reference to units about to be connected to said 20 fabric, and means for interengaging said latter units with the units of a preceding row of units in the completed fabric at intervals between the step-by-step movements.

52. In a machine for making fabric, 25 composed of transverse rows of units, each of

said units having an eye at one side of the row and a hook at the other side of the row, the hooks and eyes of adjacent rows of the fabric being directly interengaged, means for engaging an incompletely formed fabric 35 unit with the end row of a previously formed fabric length, and means for subsequently completing the formation of said unit after its engagement with the fabric.

53. In a machine for making an indefinite 40 length of fabric, composed of parallel longitudinal chains of interengaged fabric units, said units having interfitting hooks and bights at their adjacent interengaged ends, the combination of a support for a 45 previously completed length of fabric, mechanism for engaging fabric units with the ends of longitudinal chains of the fabric on said support whereby said hooks and bights are interengaged, and means for effecting 50 relative movement of the unit-engaging means and the fabric on said support.

In witness whereof, I hereunto subscribe my name this twenty fifth day of September 55 A. D., 1913.

CLARENCE H. FREDERICK.
